Primary Examiner—Louis S. Zarfas*Assistant Examiner*—Frank Martinez*Attorney, Agent, or Firm*—Lee, Mann, Smith, McWilliams, Sweeney & Ohlson**[57] CLAIM**

The ornamental design for an enclosure for a needle disposal container, as shown and described.

DESCRIPTION

FIG. 1 is a front elevational view of an enclosure for a needle disposal container according to our invention;

FIG. 2 is a side elevational view thereof, taken from the left of FIG. 1;

FIG. 3 is a side elevational view of the opposite side thereof;

FIG. 4 is a top plan view thereof;

FIG. 5 is a rear elevational view thereof;

FIG. 6 is a bottom plan view thereof; and,

FIG. 7 is a front perspective view of our enclosure for a needle disposal container, as taken from the top right.

1 Claim, 4 Drawing Sheets Fig. 6.
